COMBINED OUTLET AND CONTROL PANEL FOR AN AUTOMOBILE AIR-CONDITIONER

Don P. Dixon, 504 E. Josephine St.,
San Antonio, Tex. 78215

Filed Sept. 15, 1966, Ser. No. 3,873

Term of patent 14 years

(Cl. D14—6)

FIGURE 1 is a perspective view from the right side and top of a combined outlet and control panel for an automobile air-conditioner embodying my design;

FIGURE 2 is a perspective view from the right side and bottom thereof; and

FIGURE 3 is an elevational view from the left side thereof.

The broken lines in each of FIGURES 1 to 3 indicate an adjacent portion of the dashboard of the automobile and are for illustrative purposes only.

This application is a continuation-in-part of my co-pending application for design patent, Ser. No. 2,125, filed May 2, 1966, and entitled "Outlet and Control Panel for an Automobile Air-Conditioner," and now abandoned.

I claim:

The ornamental design for a combined outlet and control panel for an automobile air-conditioner, substantially as shown and described.
